DEFENSIVE PUBLICATION

UNITED STATES PATENT OFFICE

Published at the request of the applicant or owner in accordance with the Notice of Apr. 11, 1968, 849 O.G. 1221. Identification is by serial number of the application and the heading indicates the number of pages of specification, including claims, and of sheets of drawing contained in the application as originally filed. The file of this application is available to the public for inspection; reproduction may be purchased for 30 cents per sheet.

Applications published under the Defensive Publication Program have not been examined as to the merits of alleged invention. The Patent Office makes no assertion as to the novelty of the disclosed subject matter.

FILTER CIGARETTE ASSEMBLY HAVING ITS
PAPER OVERWRAP MECHANICALLY LOCKED
IN PLACE

Albert H. Aggett and Paul Gallagher, Kingsport, Tenn.,
assignors to Eastman Kodak Company, Rochester, N.Y.,
a corporation of New Jersey

Original application Dec. 28, 1964, Ser. No. 421,276, now
Patent No. 3,345,917, dated Oct. 10, 1967. Divided and
this application June 9, 1967. Published Apr. 8, 1969

Class 131—10

3 Sheets Drawing. 22 Pages Specification

An improved paper wrapped filamentary cigarette and filter element having a substantially cylindrical mass of filamentary tobacco smoke filter material encased in a paper wrap, the latter having an overlapped seam in which the overlying and underlying portions are perforated to mechanically lock the paper against slippage.
